UNITED STATES PATENT OFFICE.

LEONARD D. MAHAN, OF WASHINGTON, DISTRICT OF COLUMBIA, ASSIGNOR OF FIVE ONE-HUNDREDTHS TO RICHARD B. BOYLE AND FIVE ONE-HUNDREDTHS TO EDGAR W. BOYLE, BOTH OF WASHINGTON, DISTRICT OF COLUMBIA.

HELMET.

1,231,766.

Specification of Letters Patent.

Patented July 3, 1917.

Application filed July 27, 1916. Serial No. 111,747.

To all whom it may concern:

Be it known that I, LEONARD D. MAHAN, a citizen of the United States, residing at Washington, in the District of Columbia, 5 have invented certain new and useful Improvements in Helmets, of which the following is a specification.

This invention relates broadly to an improvement in head covering and particularly 10 to a helmet for the use of soldiers when at war, and has for its object to provide a helmet of such form and construction as will protect the head of the wearer from the direct fire of small guns, machine guns and 15 the like and the indirect fire of shrapnel and explosive shells, and to this end the helmet is made in two main parts, a head frame that fits upon and is secured in the usual manner on the head of the soldier 20 and an exterior cover formed preferably of an integral sheet of steel pressed into form and having a handle at its rear and a scoop or shovel shaped front which will enable the cover to be used when necessary as an 25 intrenching tool.

Another object of the invention is to provide a helmet such as described with a removable cover adjustable on the head frame whereby said cover may be tilted vertically 30 to raise and lower the extended front end for the purpose of protecting more or less of the head and face during an engagement.

A further object of the invention is to provide a helmet with a removable steel 35 cover formed of a single sheet of metal pressed into such shape as to be wholly free from angles and flat surfaces on its outer side, the entire exterior surface being more or less convexly curved so as to deflect projectiles should they strike the surface of the helmet.

A still further object of the invention is to provide a helmet for the purpose described 45 having a removable, relatively impenetrable cover that will serve as an intrenching tool, with a head frame made of metal to fit the crown of the head and preferably of skeleton form provided with suitable cushioning to render the same more comfortable to the 50 wearer, to distribute the force of blows delivered upon the helmet from the spot struck and which head frame is separated or spaced from the cover to give ample ventilation.

With these objects in view, the invention

consists of the novel construction, combination and arrangement of parts hereinafter described, pointed out in the claims and illustrated in the accompanying drawings, in which:

Figure 1. is a side elevation of the complete helmet shown in position on the head of the wearer.

Fig. 2. is a bottom view of the helmet.

Fig. 3. is a vertical cross sectional view of the same from front to rear on the line 3—3, 65 of Fig. 2.

Fig. 4. is a vertical longitudinal sectional view on the line 4—4, of the same figure.

Fig. 5. is a bottom view of the head frame with cushioning means omitted.

Fig. 6. is a detail sectional view of a portion of the helmet cover showing the slot for the attachment of the chin strap.

Fig. 7. is a perspective view of the helmet removed from the head frame to show its adaptability as an intrenching tool.

Fig. 8. is a cross-sectional view of the head frame showing pneumatic means for cushioning the same.

Fig. 9. is the perspective view illustrating the head frame without the cover 24 and adapted to be worn as a cap.

In the drawings 10 indicates a head frame made of proper shape and of suitable size to fit the head of the wearer, said frame 85 comprising a band 11 of thin metal preferably steel and two cross-strips, 12 and 13, secured to the band 11, and passing respectively from front to rear and crosswise from side to side. The bands intersect preferably at right angles at a point that will be above the crown of the head when worn and as a protection for the head a circular cushion 14, which may be of felt, pneumatic means or the like is secured against the 95 inner sides of the strips 12 and 13, at their intersection. The inner surface of the band 11 is also cushioned by a yielding strip 15 extending around the same of substantially the same width as the band and held in 100 place by a surrounding jacket 16 of leather, cloth or other material of such nature as will wear well and prove comfortable to the wearer, and hold the cushion against the band. To prevent the strips 12 and 13 from 105 bearing directly on the head of the wearer and also to protect the head of the wearer when the helmet is hit, the inner surfaces

2
of said strips are also provided with felt or other cushions 17, which with the strips themselves are incased in leather, cloth or other jacket 18. The pad 14 is also 5 closed in leather or cloth as 19 and held in position against the jacketed strips 12 and 13 by stitching or other convenient means of fastening the same.

Projecting laterally from the center of 10 each side of the band 11, perpendicular to said band and in line with each other is a stud 20, the outer end of which studs are reduced to form pivots 21 for a purpose to be described later. At the rear of the head-piece 10 there is riveted to the band 11 a 15 spring 22 made of flat spring metal and bent downwardly in a curve as shown, the free end of said spring extending downwardly behind the head-piece and having a 20 pin 23 projecting rearwardly therefrom, the terminal of said downwardly projecting end curving outwardly to form a finger piece.

Above the head-piece 10, and removably connected thereto, is the cover 24 made as 25 shown somewhat in the form of a shovel or scoop having a relatively deep head-receiving portion and a relatively shallow extension consisting preferably of a single sheet of steel pressed preferably into the shape 30 shown, that is to say, of a substantially hemispherical form at the rear where it overlies the head of the wearer, and extending in flattened curves at its forward end where it projects over and for some distance beyond the face of the wearer. As 35 will be seen, the entire exterior of the helmet is without flat surfaces and is wholly free of corners, said surface being made up of a series of curves that serve to deflect projectiles which strike the helmet. The 40 cover 24 is made of steel sufficiently strong to protect the wearer from projectiles fired by small arms and machine guns and from shrapnel fire, and sufficiently stiff to serve, 45 when removed from the head-piece, as an intrenching tool for which purpose a handle 25 of any type found most convenient is secured at the rear of cover 24.

On each side of the cover 24 near the 50 lower edge is a perforation 26, said perforations forming bearings for the pivots 21 of the studs 20 which project through said perforations from the inside. Shoulders 27 are formed on the studs at the base of the 55 pivots 21 to bear against the inner sides of the cover 24 and limit the projection of the studs through the perforations. The band 11 of the head-piece from which the studs project is sufficiently resilient to hold the 60 studs in place and which when pressed toward each other will yield and withdraw the pivots 21 from the perforation 26 whenever the cover is to be removed from the head-piece. At the lower inner central rear 65 of the head-piece 24 is a suitable rack 28

provided with a series of steps 28' into any one of which the pin 23 on the spring 22 may enter and hold the cover at various angles on the head-frame 10. By this means the extended front end of the cover may 70 be held above the range of direct vision of the wearer, or slightly tilted to protect his face when exposed to the fire of an enemy.

In connection with the helmet for holding the same on the head of the wearer, there 75 are provided two straps, one 29, connected to the cover 24 to pass under the chin of the wearer and the other 30, attached to the head-piece and extending back of the head. The chin-strap 29 has a loop 31 at each end, 80 each loop being engaged with a slot 32 in each side of the helmet preferably in front of the perforation 26. These slots are formed by cutting a short upwardly projecting tongue 33 from the material of the 85 helmet and bending the same downwardly against the inner surface of the same to form a smooth rounded edge against which the strap loop bears. The chin strap is provided with a buckle 34 to adjust the 90 length thereof to the wearer.

The head-strap 30 is riveted or otherwise fastened on the band 11 of the head-piece and fits snugly around the back of the head as shown in Fig. 1.

95 A helmet made as described affords ample protection from both direct and indirect fire and by reason of its shape and cushioning is penetrated with difficulty, and because of the cushioning on the head-piece, blows on the helmet are distributed over the head and are not concentrated at the spot receiving the blow. The head-piece, being of the skeleton form shown and spaced from the cover 24 at the front, rear and 100 sides, affords ample ventilation for the head, as air can readily circulate between the head-piece and the cover.

An important feature of the invention is 110 in the construction of the helmet cover 24 of such shape as to provide not only ample protection for the wearer but which may be, as a whole, quickly and easily removed from the headpiece and employed as an entrenching tool. The headpiece after separation from the cover may be replaced on the head and the cover due to its shovel or scoop form serves as an excellent intrenching tool, the handle 25 being grasped by one hand and the chin strap 29 serving as 115 a holding means or grip for the other hand, thus enabling the cover 24 to be readily manipulated. The cover is strong and because of its shape, very stiff, and being worn on the head when not needed for intrenching 120 purposes, serves as protection for the head, and lessens the number of tools to be carried to the front; and the loss of intrenching tools, as the soldier will after finishing with 125 or completing his work of digging, return 130

the implement to the head-piece where it will always be ready when again required. When marching if the soldier is not required to wear the helmet it may be carried 5 on the back over the pack and supported in the same manner as the present intrenching outfit carried by soldiers.

The head-piece 10 may be covered as shown in Fig. 9, by a removable cap and 10 worn in this manner so as to more fully protect the head of the wearer from the elements, etc.

Instead of using felt or like material for 5 cushioning the head-piece a rubber tube 35—see Fig. 8, is secured against the inner surface of the band 11 by a leather or textile jacket 16 which tube can be blown up like a pneumatic tire, said tube being preferably of elliptical form the longer axis dis- 20 posed vertically. At the crown of the head in place of the felt pad 14 a pneumatic cushion 36 of any suitable shape may be substituted therefor.

What I claim is:

25 1. A military helmet comprising a scoop-shaped shell having its cavity formed with a head-receiving portion and a longitudinal extension beyond the head-receiving portion, the inner surface of the shell being 30 free and unobstructed, and means for securing the helmet to the head.

2. A helmet comprising a head frame made of a band to embrace the head and cross pieces fastened thereto and extending 35 over the head, cushioning means applied to the band and cross pieces, a cushion at the intersection of said cross pieces and a convex cover made of metal secured to the head frame and extending entirely over the 40 head of the wearer and projecting in front of the same, said cover being removable from the head frame to serve as an intrenching tool.

3. A helmet comprising a skeleton head 45 frame and a cover made of metal removably secured to said head frame to serve as an intrenching tool, said head frame being formed of a metal band and two curved cross strips fastened to said band to hold

the head frame on the head, padding on the 50 interior of said band and cross strips, a protecting and holding jacket for securing said padding in position, a pad at the intersection of said cross pieces, and a stud projecting from each side of said band to engage 55 perforations in the cover for removably attaching the latter to the head frame.

4. A military helmet comprising a scoop-shaped shell having its cavity formed with a relatively deep head-receiving portion 60 and a relatively shallow longitudinal extension beyond the head-receiving portion, said shell having a handhold at its relatively deep portion.

5. A military helmet comprising a scoop-shaped shell having its cavity formed with a relatively deep head-receiving portion and a relatively shallow longitudinal extension beyond the head-receiving portion, the head-receiving portion of the shell being constructed to present an abrupt spheroidal outer deflecting surface and the extension presenting a longitudinally inclined deflecting surface merging therewith; said shell having at its relatively deep head-receiving portion, a handhold located near the edge of the cavity and leaving the abrupt portion of the shell free to receive 70 the knee of the user in assisting penetration when excavating.

6. A military helmet comprising a scoop-shaped shell having its cavity formed with a head-receiving portion and a longitudinal extension beyond the head-receiving portion in combination with a means for engaging 85 the head, the said means being removable from the shell to leave the interior of the shell clear and unobstructed for use as an intrenching tool.

7. A military helmet comprising a scoop-shaped shell having a relatively deep head-receiving portion and a relatively shallow extension, a handhold at the end of the helmet opposite to the extension, and a holding means connected to opposite sides of the helmet intermediate the ends thereof.

In testimony whereof I affix my signature.
LEONARD D. MAHAN.
